DRIVE-THROUGH RESTAURANT

Frederic P. Merrels, 5609 Wilson Lane, Bethesda, Md.

Filed July 2, 1962, Ser. No. 70,770

Term of patent 14 years

(Cl. D13—1)

Fig. 1

Fig. 2

FIG. 1 is a front elevational view of a drive-through restaurant showing my new design.

FIG. 2 is a rear elevation of FIG. 1.

FIG. 3 is a side elevation looking from the right of FIG. 1.

FIG. 4 is a side elevation looking from the left of FIG. 1.

FIG. 5 is a top plan view of FIG. 1.

I claim:

The ornamental design for a drive-through restaurant, as shown.
